UNITED STATES PATENT OFFICE

152,720

DESIGN FOR A SOFA

James Mont, New York, N. Y.

Application February 5, 1947, Serial No. 136,713

Term of patent 7 years

(Cl. D15—11)

To all whom it may concern:

Be it known that I, James Mont, a citizen of the United States of America, residing in New York, county of New York, and State of New York, have invented a new, original, and ornamental Design for a Sofa, of which the following is a specification, reference being had to the accompanying drawing, forming part thereof.

The figure on the drawing is a perspective view of a sofa showing my new design. The opposite side is substantially plain.

I claim:

The ornamental design for a sofa, substantially as shown and described.

JAMES MONT.
